UNITED STATES PATENT OFFICE.

J GABRIEL RECUERO, OF PANAMA, PANAMA.

AEROPLANE.

1,272,712.

Specification of Letters Patent. Patented July 16, 1918.

Application filed May 13, 1916. Serial No. 97,896.

To all whom it may concern:

Be it known that I, J GABRIEL RECUERO, citizen of the Republic of Panama, residing at the city of Panama, in the county of

5 Panama and State of Panama, have invented new and useful Improvements in Aeroplanes, of which the following is a specification.

This invention relates to improvements in 10 aeroplanes, and its object is to provide an aeroplane which embodies a plurality, preferably a pair, of superposed aeroplane units, each comprising a complete gliding structure with its power plant, which units 15 are rigidly connected for conjoint operation to provide a double-decked machine, whereby great speed and radius of travel may be obtained, while in the event of the stoppage of the power plant of either unit the 20 power plant of the other unit will maintain the machine in flight.

A further object of the invention is to provide a novel arrangement of the superposed units whereby increased driving 25 power and carrying capacity, together with a greater stability, will be obtained.

A still further object of the invention is to provide a double-decked aeroplane of the character described in which the power 30 plants may be separately controlled, while the steering elements of the units will operate in unison for uniform control in steering and balancing actions.

The invention consists of the features of 35 construction, combination and arrangement of parts herein fully described and claimed, reference being had to the accompanying drawings in which:—

Figure 1 is a side elevation of a flying 40 machine embodying my invention.

Fig. 2 is a front elevation of the same.

Fig. 3 is a top plan view of the machine.

Fig. 4 is a vertical longitudinal section.

Fig. 5 is a vertical transverse section on 45 the line 5—5 of Fig. 4.

Fig. 6 is a view showing the steering gear.

In carrying my invention into practice, I provide a pair of superposed aeroplane units 50 1 and 2, each of which is complete in itself with the exception of the use of launching and alighting gear upon the upper unit 2, the lower unit 1 being shown as provided in the present instance with launching and 55 alighting gear in the form of cushioned wheels 2', but it is to be understood that any

suitable type of launching and alighting gear or any suitable type of hydroplane surface, or a combination for land and water work, may be employed.

Each unit 1 and 2 disclosed in the present instance is of the monoplane type and comprises a gliding structure composed of a body 3, which may be either in the form of a fuselage or a nacelle, but which is shown in the present instance as of nacelle type and provided with a cock pit or compartment 4 for the reception of the pilot or aviator and passenger or passengers, if any. This part may be, and preferably is, of stream line 65 form and is provided at the rear end of its tail portion with a combination vertical rudder 5 and horizontal rudder or elevator 6.

The bodies 2 of the respective aeroplane units are rigidly connected and held in 70 superposed relation by intervening connecting elements of any suitable construction, which are herein shown in the form of a framing 7 of suitable vertical bars, cross bars and reinforcing wiring. The units are 75 coextensive in dimensions, but the lower unit preferably has its forward end extended to a point sufficiently in advance of the forward end of the upper unit to provide free tractor propeller clearance without the necessity 80 of spacing the units to an objectionable degree. This arrangement also gives the machine two centers of gravity and pressure, one in rear of the other, and a mean center 85 of gravity and pressure at a point between 90 the two, by means of which the balancing efficiency or stability of the machine is greatly increased.

The supporting surface of each aeroplane unit consists as usual in laterally extending 95 wings 8, which as set forth are of the monoplane type, and may have any suitable lifting curvature. For the purpose of affording communication between the two cock pits of the machine, I preferably form a part of the 100 framework 7 so that it provides a ladder 9, for convenient ascent or descent, so that in the event of damage to the power plant or controls of the unit directly carrying the pilot, he may pass therefrom to the other unit in a quick and safe manner. Sets of control wires or cables 10 and 11 lead from the respective rudders of each unit to controlling devices 10' and 11' within the cock pits, and other cables or connections 12 and 13 couple the respective horizontal and vertical rudders of the units for movement in 105 110

- unison, so that both horizontal rudders or both vertical rudders may be simultaneously operated from either of the cock pits or pilot's compartments.
5. Each unit is provided with its own power plant including a motor 14 and a tractor propeller 15, the propellers of the respective units being arranged to operate one above and in rear of the other, so that proper 10 clearance will be obtained and any interference or working resistance in the operation of the propellers avoided. The operation of the propellers in different vertical planes provides for the lifting portions of 15 their thrust being at like distances from the centers of gravity and pressure of the respective units, by means of which an efficient balance of the machine upon its supporting bank of air will be obtained.
20. It will be evident from the foregoing description that by providing the connected units, arranged as described, a machine of great speed and lifting power is obtained, since multiplied driving power will be obtained. For reasons stated, a machine of 25 superior stability is also produced, and, as the cock pit and other portions of the body of one of the units may be employed strictly for the carriage of fuel or supplies, the cruising radius of the craft will be greatly increased 30 over the machine of ordinary construction. Inasmuch as the steering gear of both units may be controlled in unison, it will be understood that the machine may be steered, balanced and maneuvered with great ease 35 and facility. Furthermore, in the event of the derangement of either power plant or set of steering controls, the remaining power plant or steering controls may be employed 40 to maintain flight and stability.
- I claim:
1. A flying machine including a pair of rigidly connected, superposed aeroplane units, each having its own power plant, a 45 companion way connecting said units, and means for controlling and steering the machine from either unit.
2. A flying machine including a pair of rigidly connected superposed aeroplane 50 units, each comprising a gliding structure
- of the monoplane type, and each having its own power plant and steering gear.
3. A flying machine comprising a pair of rigidly connected superposed aeroplane units, each having its own power plant and 55 steering gear, the steering gear of the two units being operable in unison.
4. A flying machine comprising a pair of superposed aeroplane units, each having its own power plant and steering gear, and duplicate controlling devices upon the respective units for operating said steering gear.
5. A flying machine comprising a pair of rigidly connected superposed aeroplane units, each having its own power plant and 60 steering gear, each power plant including a forward tractor propeller, said units having their bow portions arranged one in rear of the other.
6. A flying machine comprising a pair of 65 superposed aeroplane units, each having a pilot's compartment, a framing rigidly connecting said units and including a companionway connecting said compartments, propelling mechanism upon each unit, steering devices upon each unit, connected for movement in unison, and controlling devices in the respective pilot's compartments for controlling said steering devices.
7. A flying machine including a pair of 70 rigidly connected, superposed aeroplane units, each having its own power plant, sets of steering and stabilizing devices upon the respective units, and means for controlling the same from either unit.
8. A flying machine including a pair of 75 rigidly connected superposed aeroplane units, each comprising a gliding structure of the monoplane type, and each having its own power plant, steering and stabilizing 80 elements upon the respective units, and means for controlling the same from either unit.
85. In testimony whereof I, affix my signature in presence of two witnesses.

J GABRIEL RECUERO.
